UNITED STATES PATENT OFFICE.

PETER RUDD, OF CHICAGO, ILLINOIS

BAG-TYING MACHINE.

No. 813,832.

Specification of Letters Patent.

Patented Feb. 27, 1906.

Application filed May 28, 1904. Serial No. 210,182.

To all whom it may concern:

Be it known that I, PETER RUDD, a citizen of the United States, residing at Chicago, in the county of Cook and State of Illinois, have invented a certain new and useful Improvement in Bag-Tying Machines, (Case No. 1,) of which the following is a full, clear, concise, and exact description, reference being had to the accompanying drawings, forming a part of this specification.

My invention relates to bag-tying machines, and its object is to provide a machine of this kind with simplified mechanisms which enables the filling and tying of bags with greater rapidity and efficiency than has heretofore been attained.

I provide novel mechanism in the shape of closing and folding jaws which gather up and fold together the material about the mouth of the bag after filling, the jaws being provided with hooks having releasing-shields, which shields upon closure of the jaws serve to remove and release the bag material from the hooks. I also employ novel mechanism for tying the bag when it is folded by the jaws, this mechanism being actuated to loop tying-cord about the folded material, whereupon a length of tying-wire is twisted spirally about the two ends of the cord-loop, a knife-edge then serving to sever the loop, whereupon the filled and tied bag is delivered from the machine.

The various means for actuating the folding and tying mechanisms will be better understood by reference to the accompanying drawings, in which—

Figure 1 is a plan view of the machine, parts of the frame being removed, the folding-jaws being distended. Fig. 2 is a side elevation of the machine, part of the supporting-frame being removed. Fig. 3 is a plan view showing the jaws closed to fold the bag. Fig. 4 is a front elevation view of the machine. Fig. 5 is a front elevation showing the manner of supporting the bag from the hooks, the jaws being partly closed. Fig. 6 is a plan view of Fig. 5. Fig. 7 is a front elevation showing the bag folded by the jaws and the hooks released from the bag. Fig. 8 is a plan view of Fig. 7. Fig. 9 is a perspective view showing the initial position of the cord and tying mechanism. Fig. 10 is a plan view of the tying mechanism, showing the cord being looped about the folded bag. Fig. 11 shows a subsequent position of the tying mechanism. Fig. 12 is a plan view of

the tying mechanism, showing the cord completely looped and tightened about the folded bag. Fig. 13 shows the position of the tie-wire with respect to the cord-loop just before tying, and Fig. 14 shows the tie-wire twisted about the ends of the loop and the manner in which the loop is severed from the supply-cord. Figs. 15, 16, 17, and 18 are detailed views of cams employed. Fig. 19 is an isolated perspective view of a tying member, and Fig. 20 is an isolated perspective view of another tying member co-operating with the member shown in Fig. 19.

Like characters of reference refer to like parts throughout the various figures.

A supporting-frame 1 has secured to its rear end guideways 2 2, in which a slide-frame 3 is adapted to travel. A transverse driving-shaft 4 is journaled in said frame and provided with a driving-wheel 5, which may connect by a belt with a source of motive power. (Not shown.) A T-shaped cam-arm 6 is pivoted at its lower end about a transverse shaft 7, secured to the frame parallel to the driving-shaft. The upper end of this cam-arm is connected, by means of a connecting-rod 8, with the slide-frame 3. The arm 9 extends from an intermediary point between the ends of the cam-arm and carries on one end a cam-roller 10, having engagement with a cam 11, secured to the driving-shaft. Upon rotation of the driving-shaft and cam 11 the cross-head 3 will be reciprocated in the guideways 2, a spring 12 serving to return the cam-arm after actuation thereof by the cam 11. Pairs of links 13 14 and 13' 14' are symmetrically pivoted at their outer ends to opposite sides of the machine-frame 1 and are connected at their inner ends with connecting-links 15 and 15', respectively, the links of each pair being at all times parallel, the arms 15 15' being thus also at all times parallel. Links 16 16' connect the rear ends of the links 15 15', respectively, with the cross-head 3, and thus upon reciprocation of the cross-head the connecting-links 15 15' travel toward and away from each other. Near the forward end a cross-bar 17 is secured to the machine-frame. Boxes 18 18' are adapted to slide along this cross-bar 17 and are provided with a transverse opening through which may pass the connecting-links 15 and 15', respectively. These boxes 18 18' are respectively provided with depending hooks 19 and 19'. Sleeves 20 and 20', secured to the front ends of the

links 15 15', respectively, are provided with depending hooks 21 and 21'. Sleeves 22 and 22' are adapted for longitudinal motion along links 15 and 15' and are provided with longitudinal slots 23 23', in which are pins 24 24', secured to the links 15 15', respectively. These sleeves pass through the transverse openings through the boxes 18 and 18' and are provided at their forward ends with the depending hooks 25 25'. A cross-piece 26 is also secured to the machine-frame below the cross-piece 17. Near the ends of this cross-piece 26 are pivoted arms 27 27', links 28 28' connecting at one end with an intermediary point of arms 27 and 27', respectively, and at their rear ends being pivoted to the links 15 15', respectively, at a point to the rear of the cross-piece 26. As the cross-head 3 is moved rearwardly the links 15 15' will move rearwardly and parallelly together and will slide through the boxes 18 18', respectively, which boxes are slid together on the cross-piece 17, the hooks 21 21' being carried toward the boxes 18 18' with the links 15 15'. The sleeves 22 22' with their hooks are moved along the links 15 15' by the material of the bag and by coming in contact with the hook-sleeve 20 20'. At the same time the arms 27 27' are swung inwardly to cross their ends 29 29' to help fold the mouth of the bag into the position as best shown in Figs. 3, 7, and 8 after passing through the intermediate positions. (Shown in Figs. 5 and 6.) Each hook is provided with a withdrawing or releasing shield or pocket 30, which normally hangs free from the point of the hook to allow reception of the bag, but which shields upon closure of the jaw are engaged and pushed over the point of the hook to remove therefrom the bag, this position being best shown in Figs. 7 and 8, the hooks in this position offering no resistance to the removal of the bag from the machine. Opposite hooks, it will be noticed, are slightly relatively offset to enable their passage by each other upon folding of the bag, this being best shown in Figs. 1 and 8.

To compensate for the decreasing length of the bag upon folding and also to remove the strain of the filled bag from the hooks, there is provided a platform 31, pivoted to the machine-frame at 32, the forward end of the platform being connected by links 33 to one arm of a bell-crank lever 34, pivoted at its elbow about a shaft 35. The other arm of this bell-crank lever is connected by a link 36 with the end of an arm 37, projecting from the lower end of the cam-arm 6. As the cross-head 3 is thus moved rearwardly this lever mechanism will operate to raise the platform 31 and the bag thereon, thus compensating for the decreased length of the bag due to folding and also serving to release the strain from the hooks after folding of the bag. When thus folded, the bag is tied, as will be

later explained, and after removal of the tied bag from the machine the cross-head 3 will move forwardly to again distend the jaw, the hook-sleeves 22 22' being carried to their proper position by engagement of the pins 24 24' with the forward end of the wall of the slots 23 23', respectively, and the shields of the hooks will fall to again expose the points of the hooks for the reception of an empty bag.

I shall now describe the mechanism for tying the bag after folding thereof, as most clearly shown in Figs. 9 to 14.

A bearing-frame 38 is secured to the machine-frame, and at one side supports bearings 39 39, in which is pivoted a shaft 40. At one end of the shaft is secured an arm 41, carrying at its end a segmental bevel-gear 42, while between the bearings 39 a ratchet-wheel 43 is secured to the shaft 40. This ratchet-wheel is adapted for engagement by a pawl 44, carried by a pawl-frame 45, pivoted on the shaft 40, the end of said pawl-frame being pivoted to a link 46, carrying on one end a cam-roller 47, adapted for engagement with a cam 48, secured to the driving-shaft. A supporting-frame 49 is secured to the main frame of the machine and carries a bearing 50, in which is pivoted a shaft 51, having at its lower end a bevel-gear 52, engaged by the segmental gear 42 and provided at its upper end with a needle-arm 53, having at its outer end an eye 54. A gear 54 is secured to a shaft 55, pivoted in the bearings 56 56, depending from the supporting-frame 49. A pinion 57 is engaged by the gear 54 and is secured to a shaft 58, pivoted in bearings 59 59, extending upwardly from the supporting-frame 49. The other end of the shaft 58 terminates in a bevel-gear 60, having engagement with a bevel-pinion 60', secured to the end of a thimble 61, adapted to rotate in a bearing 62. The bearing 62 is secured to the machine-frame to the rear of the jaw and is provided with a longitudinal slot 63, as best shown in Figs. 9 and 10, while the thimble 61 is provided with a longitudinal radial slot 64, adapted to register with the slot 63. The thimble 61 has a flange 65 at its forward end, and thus is confined in its bearing. The thimble 61 has a passage-way 65, leading from the flange circumference to the slot 64, and the bearing 62 has a passage-way 66 therethrough in register with the passage-way 65 when the slot 64 registers with the slot 63. An end plate 67 is secured to the bearing and is provided with an opening 68, also adapted to register with the passage-ways 65 and 66. The passage-ways and opening are intended for the reception of the tie-wire, and the operation thereof will be explained subsequently. At the other end of the supporting-frame 38 from the bearings 39 I provide bearings 69 69, in which is pivoted a shaft 70, on which shaft is secured a

ratchet-wheel 71. A pawl-frame 72 pivots on shaft 70 and carries a pawl 73, the end of the pawl-frame being pivoted to a link 74, carrying on one end a roller 75, adapted to be engaged by a cam 76, secured to the driving-shaft. The inner end of the shaft 70 terminates in a bevel-gear 78, having engagement with a bevel-gear 79, secured to the lower end of a shaft 80, pivoted in a bearing 81, secured to the supporting-frame 49. The gears 78 and 79 serve to actuate rotary shuttle mechanism. (Best shown in Figs. 9, 10, 11, and 12.) This shuttle mechanism consists of a lower stationary segmental part 82, having an annular ridge 83, provided with a groove 84. The upper disk portion 85 is secured to and rotates with shaft 80, being provided with preferably four depending teeth 86, spaced ninety degrees apart and adapted to enter and pass through the groove 84 upon rotation of the disk 85. The relation of the cam 76 with the number of teeth on the ratchet-wheel 71 and the gears 78 79 is such as to cause a ninety-degree advancement of the shuttle-disk 85 at each revolution of the driving-shaft. Passing through the eye 54' of the needle-arm is the tying-cord 55', which is supplied from the reel 56', supported from the machine-frame, and upon rotation of the needle-shaft 51 the needle end carries the cord about the folded bag and into position before the opening of the groove 84, as shown in Fig. 10. A pawl-frame 88 is pivoted at the outer end of shaft 55 and carries a pawl 89, having engagement with a ratchet-wheel 90, secured to the outer end of the shaft 55. A link 91 connects the end of the pawl-frame 88 with the roller 92, having engagement with a cam 93, mounted upon the driving-shaft, and upon actuation of the ratchet mechanism by said cam mechanism the gear 54 is rotated to cause rotation of pinion-shaft 58 and the gear 60 to cause rotation of the tying-thimble 61.

The operation of the machine is as follows: The end of the tying-cord will have to be placed in the position as shown in Fig. 9—that is, the end of the cord must be clamped between the shuttle-disk 85 and the ridge 83, so that the cord will be able to enter the slot 3 of the bearing 62 and subsequently into the slot 64 of the tying-thimble. When the machine is in its normal distended position, as shown in Fig. 1, an empty bag is hung from the hooks and filled from a spout or otherwise. As the driving-shaft rotates, the cam 11 causes actuation of the jaw mechanism, as before explained, to draw together and fold the mouth of the bag and to assume a position shown in Figs. 3, 7, and 8, the folded part lying before the end of the tying-cord, the cam 11 when this is accomplished having revolved about one-fourth of a revolution in the direction of the arrow, as shown in Fig. 1. At this point the cam 48 will be rotated to

bring its surface 48' into engagement with roller 47 on arm 46 and the ratchet-wheel 43 will be actuated to cause rotation of the segmental gear 42 and pinion 52, connected with the needle-shaft 51, whereupon the needle-arm 53 will swing about the folded bag, carrying with it the cord 55', as shown in Fig. 10, the cord being drawn by the needle in place before the opening of the groove 84. The prolonged surface 48' of the cam 48 lies in the arc of a circle and the needle-arm will remain in its actuated position until the cam 76 causes actuation of the ratchet-wheel 71 to transmit motion to the shuttle-disk 85, and thus the tooth 86, Fig. 10, will engage the cord and clamp it between the disk 85 and the annular ridge 83, whereupon the shuttle-disk 85 will be rotated ninety degrees through the intermediate position, Fig. 11, to the final position, (shown in Fig. 12,) having been carried by the tooth 86 into engagement with the end of the cord clamped before the preceding tooth, and thus a loop of cord is tightly drawn by the shuttle mechanism about the folded part of the bag, the ends of this loop being disposed within the slot 64 of the tying-thimble. After this loop has been formed and drawn tight the cam 93 will become active and actuate the ratchet mechanism 90 to cause rotation of the bevel-gear 59 and of the tying-thimble 61. The end of the tie-wire *w*', which extends through the passage-ways 65 66 and into the opening 68, is sheared off at the jointure of the passage-ways 65 and 66 upon rotation of the thimble, and the end in the passage-way 65 is carried by the thimble and twisted spirally about the cord-loop ends, as shown in Figs. 13 and 14, the opening 68 serving to hold the end of the tying-piece *w*' upon rotation of the thimble with the remainder of the tying-piece. The relation between the gear 60 and the pinion 60' may be such as to cause any number of twists to be given the tying-piece, and I have shown the relation to be such as to cause the tying-piece to be twisted twice about the cord-loop ends. The cord-loop ends are thus securely tied together, and when this is accomplished a knife-blade 96, carried by the gear 60, will come into position to sever the loop ends from the remainder of the cord. The end 98 of the cord will be carried from the shuttle mechanism by the tooth engaging it upon the next rotation of the disk 85, while the end of the cord connected with the reel will be held in place by the tooth 86, as shown in Fig. 9, for receiving the next folded bag. Owing to the prolonged maximum surface of the cam 48, the needle-arm has been held in position within the shuttle mechanism, and after the tying operation is completed the platform 31 will drop the bag from the folding-jaw as the cam-roller 10 falls back to its normal position on the cam 11. Immedi-

ately after this the cam 48 allows the spring 94 to return the link 46 to cause the needle-arm to return to its normal position to carry with it the tying-cord 55', which becomes disposed before the tying mechanism, as shown in Fig. 9, to receive another folded bag. The eye of the needle is of such size as to slightly clamp the tying-cord to enable the needle to carry with it the cord upon rotation. The disposition of the disk 85 over the ridge 83 forms a chamber within the shuttle mechanism, and the end of the needle carrying the eye is bent at right angles to the needle-arm, the end of the needle and cord being thus enabled to be disposed within the shuttle-chamber without interfering with the entry of the teeth into the groove 84, and the movement of the disk is such as to prevent the teeth from interfering with the free entry and exit of the arm from the shuttle mechanism.

I thus provide a machine which is very simple in construction and its operation and which at the same time is very rapid and efficient.

25 I do not wish to be limited to the precise construction and arrangement of the parts as herein shown, as many changes may readily be made by those skilled in the art without departing from the scope or spirit of the invention.

30 I claim as new and desire to secure by Letters Patent—

1. In a bag-tying machine, the combination with means for folding the mouth of a filled bag, of a needle-arm, shuttle mechanism acting in conjunction with said needle-arm to form a loop of tying-cord about the folded part, a rotatable thimble in which said loop becomes disposed, said thimble being provided with wire, and means upon rotation of said thimble for causing said wire to be twisted about the ends of said loop to secure the folded end of the bag.

2. In a bag-tying machine, the combination with folding means for folding the mouth of a bag after filling thereof, of means independent of said folding means for looping cord about the folded part of the bag, and means for twisting wire about the ends of the loop to securely tie the bag.

3. In a bag-tying machine, the combination with a supporting-frame, of a stationary cross-bar thereon, jaw members extending forwardly from said stationary cross-bar at right angles thereto, means for suspending an empty bag between said stationary bar and said jaw members, and means for moving said jaw members parallelly toward each other and toward said stationary member, whereby the mouth of said bag is folded.

4. In a bag-tying machine, the combination with a supporting-frame, of a stationary cross-bar thereon, jaw members extending forwardly from said stationary bar, means for suspending an empty bag from said jaw

members, means for moving said jaw members toward each other and toward the stationary bar to fold the mouth of the bag, arms pivoted to said jaw members and adapted upon movement of said jaw members to assist in folding the bag and securing the folded bag against the stationary bar, and means for tying the bag when folded.

5. In a bag-tying machine, the combination with a supporting-frame, of a stationary cross-bar thereon, jaw members extending forward from said bar, hooks suspended from said jaw members, arms pivoted to said jaw members, means for causing the jaw members to move toward said stationary bar to fold the bag, and means for causing said arms to swing against the bag to assist in the folding operation and to secure the folded part of the bag against the stationary bar, means for looping cord about the folded part, and means for securing together the loop ends to securely tie the bag.

6. In a bag-tying machine, the combination with a supporting-jaw consisting of a stationary transverse rear member and forwardly-extending longitudinal side members, of hooks supported from the side members for receiving an empty bag, mechanism for causing said side members to move toward each other and toward the rear member, arms for assisting the side members to fold the mouth of the bag at the center thereof, and means upon folding of said bag for removing the bag from the hooks.

7. In a bag-tying machine, the combination with a supporting-jaw consisting of a stationary rear member and forwardly-extending side members, of hooks disposed about said jaw for supporting the bag, means for causing said side members to move toward each other and toward the stationary rear member to fold the mouth of the bag, and a shield over said hooks adapted upon closure of said jaw to remove the bag from the hooks.

8. In a bag-tying machine, the combination with a supporting-jaw consisting of a stationary rear member and forwardly-extending side members, of hooks carried by said members for supporting the bag, means causing said side members to move toward each other and toward the rear stationary member to fold the mouth of the bag, arms adapted to engage the folded portion of the bag to hold the folded portion against the rear stationary member, and means associated with each hook for removing the bag from the hooks upon closure of the jaw.

9. In a bag-tying machine, the combination with a supporting-frame, of a stationary cross-bar secured to the front end thereof, link members extending transversely over said cross-bar, the forward ends of said links forming a jaw with said cross-bar, hooks suspended in said jaw from said link members for supporting the bag, link mechanism con-

ected with said connecting-links for moving said links parallelly toward each other and toward said cross-bar to fold the mouth of the bag in the jaw, and arms pivoted to said connecting-links adapted upon movement of said links to close over a folded part of the bag to secure said part against the stationary cross-piece.

10. In a bag-tying machine, the combination with a supporting-frame, of a cross-bar secured to the forward end thereof, parallel connecting-links extending transversely over said cross-bar, links connecting said connecting-links with the machine-frame, a cross-head connected with the rear ends of said connecting-links, cam mechanism for moving said cross-head to cause said connecting-links to move parallelly toward each other and toward the rear of the machine, the forward ends of said connecting-links forming a jaw with said stationary cross-bar, hooks for said jaw suspended from said connecting-links, actuation of said cross-head causing the said jaws to close the fold of the mouth of the bag, arms pivoted to said connecting-links, the ends of said arms adapted upon actuation of said connecting-links to cross over the folded part of the bag to secure this part against the stationary bar, means for removing the hooks from the bag after folding thereof, and means for tying the folded bag.

11. In a bag-tying machine, the combination with a supporting-frame, of a stationary cross-bar secured to the front end thereof, journal-boxes adapted for sliding engagement with said stationary bar, parallel connecting-links adapted to slide through said journal-boxes and transversely across said stationary bar, links connecting the ends of said connecting-links with the machine-frame, a cross-head connected with the rear ends of said connecting-links, cam mechanism for reciprocating said cross-head to cause said connecting-links to move parallelly toward each other and toward the rear of the machine, the forward end of said connecting-links forming a jaw with said stationary bar, hooks for said jaw suspended from said connecting-links and from said journal-boxes for supporting the bag, the mouth of said bag being folded upon rearward motion of said cross-head, arms pivoted to said connecting-links, the ends of said arms being adapted to engage over the folded part of the bag to secure this part against the stationary bar, means for removing the hooks from the bag after folding thereof, and means for tying the bag upon folding.

12. In a bag-tying machine, the combination with a supporting-frame, of a stationary cross-bar at the forward end thereof, journal-boxes adapted to slide on said cross-bar, sleeves passing through transverse openings through said boxes, connecting members passing through said sleeves and transversely

over said stationary bar to form a jaw at their forward end with said bar, links connecting the ends of said connecting members with the machine-frame, a cross-head connected with the rear ends of said connecting members, means for moving said cross-head to bring said connecting members toward each other and toward the rear of the machine to close the jaw, hooks secured to the forward ends of said connecting-links, hooks secured to said boxes and hooks secured to said sleeves, said hooks serving to support the bag to be tied, said bag being folded at the mouth upon closure of said jaw, arms connected to said connecting members, means for closing the ends of said arms over the folded part of the bag upon rearward travel of the cross-head to secure the folded part against the stationary cross-bar, and means for tying the bag when folded.

13. In a bag-tying machine, the combination with means for folding the mouth of a filled bag, of means independent of said folding means for disposing a cord-loop about the folded part, and means for applying turns of wire about the loop ends adjacent to the folded part, the loop ends remaining stationary.

14. In a bag-tying machine, the combination with means for folding the mouth of a filled bag, of a needle-arm adapted to form a loop of tying-cord about the folded part, a slotted thimble in which said loop becomes disposed, means for inserting wire in said thimble, and means for rotating said thimble to tie said wire about the loop ends, whereby said bag is tied.

15. In a bag-tying machine, the combination with means for folding the mouth of a filled bag, of a needle-arm, shuttle mechanism acting in conjunction with said needle-arm to form a loop of tying-cord about the folded part of the bag independent of the folding means, and means for twisting a length of wire about the ends of said loop, whereby said bag is tied.

16. In a bag-tying machine, the combination with means for folding the mouth of a filled bag, of a needle-arm, shuttle mechanism acting in conjunction with said needle-arm to form a loop of tying-cord about the folded part, a thimble having a slot in which said loop becomes disposed, said thimble being provided with wire extending radially therethrough into said slot, and means for rotating said thimble to twist said wire about the ends of said loop.

17. In a bag-tying machine, the combination with means for folding the mouth of a filled bag, of a needle-arm for conveying tying-cord, a slotted thimble disposed before the folded portion, a bearing in which said thimble may revolve, said bearing having a slot adapted to register with the slot through said thimble, there being a passage-way extending through said bearing and thimble.

into said thimble-slot, shuttle mechanism acting in conjunction with said needle-arm to form a loop of tying-cord about the folded part of the bag and to dispose the ends of said loop in said thimble-slot, means for causing rotation of said thimble within said bearing, and means upon such rotation for causing a length of wire shearding through said radial passage-ways and into the thimble-slot to be sheared off and twisted about the ends of said cord-loop.

18. In a bag-tying machine, the combination with means for folding the mouth of a filled bag, of a needle-arm adapted to convey 15 tying-cord, a thimble having a longitudinal slot disposed before the folded part of the bag, a bearing in which said thimble may rotate, said bearing having a longitudinal slot adapted to register with the slot through said 20 thimble, there being a passage-way extending radially through said bearing and said thimble-walls and through the thimble-slot, an end plate secured to said bearing and provided with an opening for receiving the end 25 of a feed-wire extending through said passage-way, shuttle mechanism for forming a loop of tying-cord about the folded part of the bag and for disposing the loop ends within the slot through said thimble, and means 30 for rotating said sleeve within said bearing, whereby the end is sheared from the feed-wire and whereby said end is twisted about the end of the cord-loop.

19. In a bag-tying machine, the combination with means for folding the mouth of a filled bag, of a needle-arm for conveying tying-cord from a supply-reel, a thimble having a longitudinal slot disposed with its end before the folded part of the bag, said thimble 35 having a radial passage-way extending into said slot, a stationary part adjacent to the end of said slot having an opening for receiving a wire extending through said slot, shuttle mechanism acting in conjunction with 40 said needle-arm for forming a loop of tying-cord about the folded part of the bag and for disposing said loop ends within said slot, means for rotating said thimble, whereby 45 said wire is twisted about the end of said loop, and means for severing said loop from the 50 remainder of the cord.

20. In a bag-tying machine, the combination with means for folding the mouth of a filled bag, of a needle-arm for conveying tying-cord from a supply-reel, a thimble having a longitudinal slot disposed with its end before the folded part of the bag and having a 55 passage-way extending radially into said slot, a stationary part adjacent to the end of said slot having an opening for receiving a wire extending through said slot, shuttle mechanism acting in conjunction with said 60 needle-arm for forming a loop of tying-cord about the folded part of the bag and for disposing said loop within said slot, teeth at the

end of said thimble, a gear-wheel engaging said teeth for causing rotation of said thimble to cause said wire to be twisted about the loop ends close to the folded part of the bag, a knife secured to said gear-wheel, and means 70 for causing said knife to sever said loop from the remaining cord after said wire has become twisted about the loop ends.

21. In a bag-tying machine, the combination with a thimble having a longitudinal slot 75 extending radially to its center, of a needle-arm, shuttle mechanism acting in conjunction with said needle-arm, said needle-arm and shuttle mechanism being normally disposed to extend tying-cord across the end of 80 said slot, means for folding the mouth of a filled bag and disposing the folded part before the end of said slot and before said cord, means for causing actuation of said needle-arm to convey said tying-cord toward said 85 shuttle to be looped about the folded portion of the bag, means for causing said shuttle mechanism to convey the ends of the formed loop into said thimble-slot across a wire extending into said slot, and means for causing 90 rotation of said thimble for twisting said wire about the loop ends.

22. In a bag-tying machine, the combination with a thimble having a longitudinal slot 95 extending radially to its center, of a needle-arm normally disposed to one side of said thimble for carrying tying-cord, rotary shuttle mechanism disposed at the other side of said thimble, said tying-cord normally passing through the needle-eye and by the end of 100 said thimble-slot, the end of said cord being held by said shuttle mechanism, means for folding the mouth of a filled bag and disposing the folded portion before the end of the thimble-slot and against the tying-cord, 105 means for causing actuation of said needle-arm to carry the tying-cord toward said shuttle mechanism to form a loop about the folded portion of the bag, means for causing rotation of said shuttle mechanism to dispose 110 the ends of said formed loop within the thimble-slot and across a wire extending into said thimble-slot, and means for causing rotation 115 of said thimble to cause said wire to be twisted about the ends of said loop close to the folded portion of the bag.

23. In a bag-tying machine, the combination with a thimble having a longitudinal slot extending to its center and having a transverse passage-way for receiving a wire extending into said slot, of a needle-arm normally disposed to one side of said thimble for carrying tying-cord, rotary shuttle mechanism disposed at the other side of said thimble, 120 said tying-cord normally passing through the needle-eye and by the end of said thimble-slot, the end of said cord being held by said shuttle mechanism, means for folding the mouth of a filled bag and disposing the folded portion before the end of the thimble-slot and 125

- against the tying-cord, means for causing actuation of said needle-arm to carry the tying-cord toward said shuttle mechanism to form a loop about the folded portion of the bag, means for causing rotation of said shuttle mechanism to dispose the ends of said formed loop within the thimble-slot across the wire therein, and means for causing rotation of said thimble to cause said wire to be twisted about the ends of said loop close to the folded part of the bag.
24. In a bag-tying machine, the combination with a thimble having a longitudinal slot extending to its center, of a needle-arm normally disposed to one side of said thimble for carrying tying-cord, rotary shuttle mechanism disposed at the other side of said thimble, said tying-cord normally passing through the needle-eye and by the end of said thimble, slot, the end of said cord being held by said shuttle mechanism, means for folding the mouth of a filled bag and disposing the folded portion before the end of the thimble-slot and against the tying-cord, means for causing actuation of said needle-arm to carry the tying-cord toward said shuttle mechanism to form a loop about the folded portion of the bag, means for causing rotation of said shuttle mechanism to dispose the ends of said formed loop within the thimble-slot, there being a passage-way near the forward end of said thimble extending radially into said slot for receiving a wire, a stationary member before said slot having an opening for receiving the end of said wire, and means for causing rotation of said thimble, whereby said wire is twisted about the ends of the loop close to the folded part of the bag.
25. In a bag-tying machine, the combination with a thimble having a longitudinal slot extending radially to its center, of a needle-arm normally disposed to one side of said thimble for conveying tying-cord, rotary shuttle mechanism disposed at the other side of said thimble, said tying-cord normally passing through the needle-eye and by the end of said thimble-slot, the end of said cord being held by said shuttle mechanism, means for folding the mouth of a filled bag and disposing the folded portion before the end of the thimble-slot and against the tying-cord, means for causing actuation of said needle-arm to carry the tying-cord toward said shuttle mechanism to form a loop about the folded portion of the bag, means for causing rotation of said shuttle mechanism to dispose the ends of said formed loop within the thimble-slot, there being a passage-way near the forward end of said thimble extending radially into said slot for receiving a wire, a stationary member before said slot having an opening for receiving the end of said wire, and means for causing rotation of said thimble, whereby said wire is twisted about the ends of the loop close to the folded part of the bag.
26. In a bag-tying machine, the combination with a thimble having a longitudinal slot extending radially to its center, of a bearing in which said thimble may rotate, said bearing having a horizontal slot adapted to register with said thimble-slot, a needle-arm normally disposed at one side of said thimble for conveying tying-cord, rotary shuttle mechanism at the other side of said thimble, said tying-cord normally passing through the needle-eye and disposed before the mouth of said thimble-slot, the end of said cord being secured to said shuttle, means for folding the mouth of a filled bag and disposing the folded portion before the mouth of the thimble-slot and against the cord, means for causing rotation of said needle-arm toward said shuttle to form a loop of tying-cord about the folded part of the bag, means for causing rotation of the shuttle mechanism to carry the ends of the loop through the bearing-slot and into the thimble-slot and to tighten the loop, there being a passage-way extending radially through said bearing and thimble, a plate secured to said bearing extending forwardly before the mouth of the thimble-slot, said plate having an opening for securing the end of a feed-wire extending through said radial passage-way, means for causing rotation of said thimble to shear from said feed-wire the part within the thimble, and means for causing said part to be twisted about the ends of the loop disposed within said slot.
27. In a bag-tying machine, the combination with a thimble having a longitudinal slot extending radially to its center, of a bearing in which said thimble may rotate, said bearing having a horizontal slot adapted to register with said thimble-slot, a needle-arm normally disposed at one side of said thimble for conveying tying-cord, rotary shuttle mechanism at the other side of said thimble, said tying-cord normally passing through the needle-eye and disposed before the mouth of said thimble-slot, the end of said cord being secured to said shuttle, means for folding the mouth of a filled bag and disposing the folded portion before the mouth of the thimble-slot and against the cord, means for causing rotation of said needle-arm toward said shuttle to form a loop of tying-cord about the folded part of the bag, means for causing rotation of the shuttle mechanism to carry the ends of the loop through the bearing-slot and into the thimble-slot and to tighten the loop, there being a passage-way near the mouth of said thimble-slot extending radially and forwardly through said bearing and said thimble for receiving a wire, an end plate secured to said bearing and disposed before the mouth of the thimble-slot, said plate having an opening for receiving the wire extending through said passage way,

- and means for causing rotation of said thimble to shear from said wire the part within the thimble and to twist said part about the ends of the loop within said slot.
28. In a bag-tying machine, the combination with a thimble having a longitudinal slot extending radially to its center, of a bearing in which said thimble may rotate, said bearing having a horizontal slot adapted to register with said thimble-slot, a needle-arm normally disposed at one side of said thimble for conveying tying-cord, rotary shuttle mechanism at the other side of said thimble, said tying-cord normally passing through the needle-eye and disposed before the mouth of said thimble-slot, the end of said cord being secured to said shuttle, means for folding the mouth of a filled bag and disposing the folded portion before the mouth of the thimble-slot and against the cord, means for causing rotation of said needle-arm toward said shuttle to form a loop of tying-cord about the folded part of the bag, means for causing rotation of the shuttle mechanism to carry the ends of the loop through the bearing-slot and into the thimble-slot and to tighten the loop, there being a passage-way near the mouth of said thimble-slot extending radially and forwardly through the walls of said bearing and said thimble for receiving a wire, an end plate secured to said bearing and disposed before the mouth of the thimble-slot, said plate having an opening for securing the end of said wire extending through said passage-way, means for causing rotation of said thimble to shear from said wire the part within the thimble and to twist said part about the ends of the loop within said slot, and means for severing the loop from the remainder of the cord after said wire is twisted.
29. In a bag-tying machine, the combination with a thimble having a longitudinal slot extending radially to its center, of a bearing in which said thimble may rotate having a horizontal slot adapted to register with said thimble-slot, a needle-arm normally disposed at one side of said thimble for conveying tying-cord, rotary shuttle mechanism at the other side of said thimble, said tying-cord normally passing through the needle-eye and disposed before the mouth of said thimble-slot, the end of said cord being secured to said shuttle, means for folding the mouth of a filled bag and for disposing the folded portion before the mouth of the thimble-slot and against the cord, means for causing rotation of said needle-arm toward said shuttle to form a loop of tying-cord about the folded part of the bag, means for causing rotation of the shuttle mechanism to carry the ends of the loop through the bearing-slot and into the thimble-slot and to tighten the loop, there being a passage-way near the mouth of said thimble-slot extending radially and forwardly through the walls of said bearing and
- said thimble for receiving a wire, an end plate secured to said bearing and disposed before the mouth of the thimble-slot, said plate having an opening for securing the end of said wire extending through said passage-way, teeth at the rear end of said thimble, a gear engaging said teeth for causing rotation of said thimble to shear from said feed-wire the part within the thimble and to twist said part about the ends of the loop disposed in said thimble-slot, and a knife secured to said gear-wheel adapted after said wire part is twisted about said loop to sever said loop from the remainder of the cord.
30. In a bag-tying machine, the combination with means for folding the mouth of a filled bag, of a needle-arm normally disposed at one side of the folded part of the bag for carrying tying-cord, shuttle-mechanism disposed at the other side of said folded part, said tying-cord normally extending from the end of said needle-arm and passing by one side of said folded part, the end of said cord being secured to said shuttle mechanism, a stationary segmental part for said shuttle mechanism having an annular ridge provided with a groove, a rotatable disk disposed over said ridge, teeth on said disk adapted to enter said groove, means for causing said needle-arm to loop said cord about the folded part of the bag and to dispose the cord before the mouth of said groove, means for causing rotation of said disk, whereby a tooth engages the cord conveyed before said groove by said needle-arm to clamp said cord and to tighten the loop about said folded part, and means for twisting a wire about the ends of the loop.
31. In a bag-tying machine, the combination with means for folding the mouth of a filled bag, of a needle-arm normally disposed at one side of the folded part of the bag for carrying tying-cord, shuttle mechanism disposed at the other side of said folded part, said tying-cord normally extending from the end of said needle-arm and passing by one side of said folded part, a stationary segmental part for said mechanism having an annular ridge provided with a groove, a rotatable disk disposed over said ridge, teeth on said disk adapted to enter said groove, means for causing said needle-arm to loop said cord about the folded part of the bag and to dispose the cord before the mouth of said groove, means for causing rotation of said disk, whereby a tooth engages the cord conveyed before said groove by said needle-arm to clamp said cord and to tighten the loop about said folded part, means for twisting a wire about the ends of the loop, and means for severing the tied loop from the remainder of the cord.
32. In a bag-tying machine, the combination with means for folding the mouth of a filled bag, of a needle-arm normally disposed at one side of the bag, for carrying tying-cord,

shuttle mechanism disposed at the other side of the bag, a normally stationary part for said shuttle mechanism having an annular groove, a rotatable disk disposed above said groove, 5 teeth extending from said disk adapted to enter and pass through said groove, said tying-cord normally passing through the needle-eye and clamped at its end in said groove by one of said teeth, said cord being normally disposed at one side of the folded part, means for causing rotation of the needle-arm to form a loop about the folded part of the bag and to convey the cord before the mouth of said groove, means for causing rotation of said 10 disk, whereby a tooth engages the cord before the groove and carries the cord to be clamped between the groove and disk, further rotation of the disk causing the loop to be tightened about the folded portion of the bag, and 15 means for twisting wire about the loop ends close to the folded part of the bag.

33. In a bag-tying machine, the combination with a thimble having a horizontal slot extending radially to its center, of a needle-arm normally disposed at one side of said thimble for conveying tying-cord, shuttle mechanism disposed at the other side of said thimble, a stationary segmental part for said shuttle mechanism having an annular groove, 20 a rotatable disk disposed above said segmental part, teeth extending from said disk adapted to enter and to pass through said groove, said tying-cord normally extending through the needle-eye and before the mouth of said thimble-slot, the end of said cord being clamped before one tooth between said disk and segmental part, means for folding the mouth of a filled bag and disposing the folded part before the mouth of said thimble and before said cord, means for causing rotation of said needle-arm to form a loop about said folded part and to convey the cord before the mouth of said annular groove, means for causing rotation of said disk, whereby another tooth engages the cord conveyed by the needle-arm to clamp said cord between the disk and segmental part, continued rotation of said disk causing both said teeth to carry the ends of the formed loop into said thimble-slot and to tighten said loop, and means for causing rotation of said thimble to twist a wire in said thimble about said loop ends adjacent to the folded part of the bag.

34. In a bag-tying machine, the combination with a thimble having a horizontal slot extending radially to its center, of a needle-arm normally disposed at one side of said thimble for conveying tying-cord, shuttle mechanism disposed at the other side of said thimble, a stationary segmental part for said shuttle mechanism having an annular groove, a rotatable disk disposed above said segmental part, teeth extending from said disk adapted to enter and to pass through said groove, said tying-cord extending through

the needle-eye and before the mouth of said thimble-slot, the end of said cord being clamped before one tooth between said disk and segmental part, means for folding the mouth of a filled bag and disposing the folded part before the mouth of said thimble and before said cord, means for causing rotation of said needle-arm to form a loop about said folded part and to convey the cord before the mouth of said annular groove, means for causing rotation of said disk, whereby another tooth engages the cord conveyed by the needle-arm to clamp said cord between the disk and segmental part, continued rotation of said disk causing both said teeth to carry the ends of the formed loop into said thimble-slot and to tighten said loop, said thimble having a wire extending therefrom, means for causing rotation of said thimble to twist said wire about said loop ends adjacent to the folded part of the bag, and means for severing the tied loop from the remainder of the cord.

35. In a bag-tying machine, the combination with a thimble having a horizontal slot extending radially to its center, of a needle-arm normally disposed at one side of said thimble for conveying tying-cord, shuttle mechanism disposed at the other side of said thimble, a stationary segmental part for said shuttle mechanism having an annular groove, a rotatable disk disposed above said segmental part, teeth extending from said disk adapted to enter and to pass through said groove, said tying-cord extending through the needle-eye and before the mouth of said thimble-slot, the end of said cord being clamped before one tooth between said disk and segmental part, means for folding the mouth of a filled bag and disposing the folded part before the mouth of said thimble and before said cord, means for causing rotation of said needle-arm to form a loop about said folded part and to convey the cord before the mouth of said annular groove, means for causing rotation of said disk, whereby another tooth engages the cord conveyed by the needle-arm to clamp said cord between the disk and segmental part, continued rotation of said disk causing both said teeth to carry the ends of the formed loop into said thimble-slot and to tighten said loop, there being a passage-way near the mouth of said thimble extending radially and forwardly through the thimble-wall and into the slot for receiving a wire extending therethrough, means for securing the inner end of said wire, and means for rotating said thimble, whereby said wire is twisted spirally about the ends of the cord within the thimble-slot.

36. In a bag-tying machine, the combination with a thimble having a horizontal slot extending radially to its center, of a needle-arm normally disposed at one side of said thimble for conveying tying-cord, shuttle

mechanism disposed at the other side of said thimble, a stationary segmental part for said shuttle mechanism having an annular groove, a rotatable disk disposed above said segmental part, teeth extending from said disk adapted to enter and to pass through said groove, said tying-cord extending through the needle-eye and before the mouth of said thimble-slot, the end of said cord being clamped before one tooth between said disk and segmental part, means for folding the mouth of a filled bag and disposing the folded part before the mouth of said thimble and before said cord, means for causing rotation of said needle-arm to form a loop about said folded part and to convey the cord before the mouth of said annular groove, means for causing rotation of said disk, whereby another tooth engages the cord conveyed by the needle-arm to clamp said cord between the disk and segmental part, continued rotation of said disk causing both said teeth to carry the ends of the formed loop into said thimble-slot and to tighten said loop, a wire to said thimble, teeth at the rear end of said thimble, a gear-wheel engaging said teeth for causing rotation of said thimble to twist a wire passing through said thimble spirally about the ends of said cord-loop, and a knife secured to said gear-wheel adapted after said wire is twisted about the loop ends to cut said loop from the remainder of the cord.

37. In a bag-tying machine, the combination with hooks for suspending the distended bag, means for causing said hooks to converge to fold the mouth of the filled bag, means for holding the folded part in position after folding, means for releasing the hooks from the folded bag, means for forming a loop of tying-cord about the folded part, and means for twisting a wire about the ends of the loop adjacent to the folded part.

38. In a bag-tying machine, the combination with hooks from which the distended bag is suspended, means for converging said hooks to fold the mouth of the filled bag, means for holding the folded part in position after folding, shields for said hooks adapted to push the bag from the hook-points after folding thereof, means for forming a loop of tying-cord about the folded part, and means for spirally twisting a wire about the ends of the loop adjacent to the folded part.

39. In a bag-tying machine, the combination with a supporting-frame, of a stationary transverse bar at the front part thereof, longitudinal bars extending across said transverse bar, link members connecting said longitudinal bars with the machine-frame, a cross-head at the end of said supporting-frame, a driving-shaft pivoted in said frame, a cam mounted on said driving-shaft, and cam-levers connected with said cross-head and said cam, rotation of said shaft causing

actuation of said cam to move the cross-head rearwardly whereby the longitudinal bars are brought toward each other and moved rearwardly, hooks supported from said longitudinal bars in front of said cross-arms for receiving a bag, the mouth of said bag being folded toward the center upon closure of said longitudinal bars.

40. In a bag-tying machine, the combination with hooks from which the distended bag is suspended, means for converging said hooks to fold the mouth of the filled bag, and means for raising the bag during the folding operation.

41. In a bag-tying machine, the combination with hooks from which the distended bag is suspended, means for converging said hooks to fold the mouth of the filled bag, means for raising the bag during the folding operation, means for tying the folded part of the bag, means after tying for releasing the bag from the hooks, and means after releasing the bag from the hooks for again lowering said bag to its normal position.

42. In a bag-tying machine, the combination with hooks from which the distended bag is suspended, a platform for holding the filled bag, means for causing the hooks to move together to fold the mouth of the bag toward the center thereof, means for raising said platform with the bag during the folding operation, means for tying the bag after folding thereof, means for releasing the bag from the hooks, and means for thereafter lowering said platform to carry the bag to its normal position.

43. In a bag-tying machine, the combination with a supporting-frame, of a stationary cross-bar thereon, longitudinal parallel cross-bars co-operating with said transverse bar, a cross-head connected with said longitudinal bars, a driving-shaft pivoted in said frame, a cam mounted on said driving-shaft, a cam-arm associated with said cam and connected with said cross-head, hooks suspended from the longitudinal bars in front of said cross-bar for supporting the bag to be filled, a platform below the bag, lever mechanism connecting said platform with said cam-arm, actuation of said driving-shaft causing rotation of said cam to move the cross-head to carry the longitudinal arms toward each other and toward the cross-bar whereby said hooks are brought together to fold the mouth of the bag, said platform during said folding operation being moved by said lever mechanism to raise the bag, and means for tying the bag after folding thereof, further rotation of said cam allowing release of said longitudinal members and of said platform whereby the tied bag is released from the hooks and returned to its normal position.

44. In a bag-tying machine, the combination with a transverse bar, of longitudinal

parallel bars extending across said transverse bar, bearing-boxes adapted to slide on said cross-bar and through which said longitudinal bars may slide, supporting-hooks suspended from said boxes, supporting-hooks suspended from said longitudinal bars in front of said transverse bar, sleeves passing over said longitudinal bars and through said boxes, supporting-hooks suspended from

5

o said sleeves, means for causing said longitudinal bars to be moved rearwardly and parallelly toward each other whereby the hooks are brought together and whereby the mouth of a bag suspended from said hooks is folded at

15 the center of the bag.

45. In a bag-tying machine, the combination with supporting-bars, of hooks suspended from said bars, a shield over each hook normally disposed to allow application of a

20

25

distended bag to the hooks, means for causing said bars to be moved together to fold the mouth of the bag, and means upon such movement of the bars for causing the shields

on the hooks to be engaged to push the bag from the hooks.

46. In a bag-tying machine, the combination with a stationary transverse bar, of longitudinal parallel bars extending across the transverse bar, hooks suspended from said longitudinal bars in front of the transverse bar, a shield for each hook, said shields being normally disposed to permit application of a bag to the hooks, means for causing said longitudinal bars to be moved rearwardly and parallelly together to fold the mouth of the bag, the shields of the hooks on one longitudinal bar being engaged by the opposite longitudinal bar upon closure of the bars to cause the bag to be pushed from the hooks whereby said bag is released.

In witness whereof I hereunto subscribe my name this 26th day of May, A. D. 1904.

PETER RUDD.
